UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

RAILWAY CAR.

Application filed January 10, 1924. Serial No. 685,297.

To all whom it may concern:

Be it known that I, THOMAS ELLIOTT, a citizen of the United States, residing at Cincinnati, in the county of Hamilton and State of Ohio, have invented certain new and useful Improvements in Railway Cars, of which the following is a specification, reference being had therein to the accompanying drawing.

10 This invention relates to railway cars and more particularly to vestibule sash and operating mechanism therefor.

The general object of the invention is to provide an easily operated vestibule sash 15 which a motorman or other operator can open and close with the greatest facility and which when closed will be weather tight and when open will be retained in place, this general object being carried into effect by 20 combining with the sash a swinging support

Another object of the invention is the provision of a double acting spring, which when combined with the swinging operating device 25 acts to keep the sash tightly against the vestibule, posts when the window is closed, and which also acts when the window is open to keep the sash in its then position to prevent rattling.

30 A further object of the invention is to obtain an increased glass or light area, which is accomplished by providing the vestibule with seats to such an extent that the inner portions of the sash rails will extend into the window opening between these posts to a limited distance, thereby affording the operator an increased vision space.

In cars now generally in use, the vestibule windows are dropped in a pocket when it is desired to open them. This construction is objectionable because it requires not only the use of both hands of the motorman or other operator when it is desirable or necessary to open or close the window, but also because a great many windows are broken by reason of the operator losing his grasp on the strap or other means provided for raising or lowering the window, whereupon the sash drops into the pocket with a severe jar and resultant breakage of the glass. This frequent breakage of the glass results in inconvenience and expense. My present invention is designed to overcome these objections and at the same time provide a more

economical and satisfactory construction with the greatest possible ease of operation.

In the accompanying drawings: Figure 1 is a sectional view substantially on the line 1—1 of Figure 2, and looking in the direction of the arrows.

Figure 2 is a front elevation of the vestibule of a railway car showing my invention applied thereto.

Figure 3 is a vertical sectional view on the line 3—3 of Figure 2, and looking in the direction of the arrows.

Figure 4 is a vertical sectional view taken on the line 4—4 of Figure 2 and looking in the direction of the arrows, and

Figure 5 is a vertical sectional view taken on the line 5—5 of Figure 2.

In these drawings I have shown so much of the vestibule of a railway car or other

vehicle as is necessary to an understanding of my invention, in which 1 designates the front wall of the vestibule. Vertical posts 2, 3, 4 and 5 which rest on the floor of the

vestibule extend up to and support the roof structure thereof. In the upper part of the vestibule between the vertical posts are open spaces adapted to receive window sash. For

purposes of illustration I have shown the open space between the posts 2 and 3 as

also between the posts 4 and 5 equipped with a stationary sash, while the space between the posts on the outside with sash or window posts 3 and 4, or central space, is provided

with a movable sash. In carrying out my invention I have utilized the central sash window opening between these posts to a limited distance, thereby affording the operator an increased vision space.

The sill on the inside of the vestibule for

the several sashes is designated 6, while the sill on the outside of the vestibule is shown

at 7. A sash 8 carries glass 9 and rests on the outer sill 7 and abuts against the sill 6.

A bracket 10 having a bearing is secured to the vestibule wall beneath the central opening by screws 11. Above the central opening substantially in line with the bracket 10 is another bracket 12 having a bearing and

fastened to the wall of the vestibule by screws 13. On the right hand side of the

sash in the central opening, near the top and bottom thereof, are secured two brackets 14 by screws 15. A substantially U-shaped rod is mounted in these several brackets 10, 12 and 14, and constitutes a

support 16, capable of a swinging movement, for a sash, in this instance the central sash. This support consists of a vertical portion 17 pivotally mounted in the bearing 5 in the bracket 10, a horizontal portion 18, a vertical portion 19, horizontal portion 20, diagonal portion 21, horizontal portion 22, and a vertical portion, which latter is pivotally mounted in the bearing in the bracket 10 12. The vertical portion 19 of the support 16 is extended slightly beyond the horizontal portions 18 and 20 and mounted in the brackets 14 so that the support for the central sash may be easily moved. A spring 23 15 is secured at one end of the horizontal portion 22 of the support 16 by a pin 24 or other suitable means and at the other end to the outer end of the bracket 12 by a pin 25. This spring serves to hold the window sash 20 tightly in place when the window is closed and also prevents the sash from rattling when in open position by reason of its eccentric center connections between the bracket and the support 16.

25 I provide means at the left hand side of the central sash for guiding said sash when it is moved into open position which is indicated by the dotted lines in Figure 1. This means consists of guideways or tracks 30 26, preferably of L-shaped form in cross section, their base portions being rigidly secured to the car structure by screws 27, or in any other suitable manner. One of these guideways or tracks is located at the bottom, 35 and the other at the top of one of the side-window openings, as clearly seen in Figure 5. To the central sash 8 is secured by screws 28 on the left hand side, near the top and bottom thereof, brackets 29. At the 40 end of each bracket 29 there is provided a recess into which is fitted a stem portion 30 on the outer end of which there is an enlarged portion 30^a, having a slot 31 adapted to encompass the vertical or track member 45 of the guideway 26. The stem portion 30 having the member 30^a is held in position by means of a washer 32 and cotterpin 33 and has pivotal movement in the bracket 29.

50 In Figure 4 I have shown in detail the lower track member and guide member adapted to travel thereon. The upper track member is similarly mounted in an inverted position which is clearly shown in 55 Figure 5. A bumper 34, of rubber or other suitable material, as shown in Figure 1, is provided at the end of each track member 26 in order to cushion the action of the sash when it is slid into open position.

60 From the foregoing description the operation of my improved vestibule sash construction will be readily understood.

In brief it is as follows:

Assume the motorman or other operator 65 is located in front of the central opening

of the vestibule with the sash closed when the swinging support will be in the position shown in Figure 2 and the rollers carried by the brackets 29 will be on the track member 26. By pushing outwardly on the support or the central sash against the tension of the spring 23 until the spring has reached its maximum stretch, when it begins to assume over center position, the sash which is carried by the swinging support is caused to swing outwardly upon its pivots, guided by the U-shaped rod or support and the track members until the sash has reached its full open position by coming to rest against its safety stop. When it is desired to close the window the operator simply draws the rod toward him, thereby overcoming the tension of the spring and causing the sash to return to closed position through its pivotal connection with the swinging support and the sliding guideway.

Having thus fully described my invention, what I claim as new and desire to secure by Letters Patent is:—

1. In a railway car, a vestibule having an opening and a sash adapted to close and open the same, an actuating support to carry said sash and move it from closed to open position, and vice versa, and a guide-way to guide said sash in its movements from closed to open position, and vice versa. 90

2. In a railway car, a vestibule having a plurality of window openings, adapted to receive sashes, a swinging actuated support to carry one of said sashes from closed to open position, and vice versa, and a guide-way to guide said sash in its movements from closed to open position, and vice versa. 100

3. In a railway car, a vestibule having a plurality of openings, a window sash for each opening, an actuating support for one of said sashes, means for attaching said support to the vestibule and to said sash, a guideway mounted on said vestibule, and means carried by said sash having the support to slide on said guideway, whereby the said sash may be moved into open and closed positions by manipulating the actuating support. 105

4. In a railway car, a vestibule having a plurality of openings adapted to receive window sashes, an actuating support for one of said sashes, a guideway to guide said sash having the support into open and closed positions, and means to hold said sash tightly 110 in place when the window is closed and to prevent said sash from rattling when the window is open. 120

5. A railway car, having a vestibule provided with a central opening and one opening at either side thereof, fixed window sashes in the side openings, a removable sash for the central opening, an actuating support to sustain said latter sash and to move to and from its open and closed posi- 125 130

tions and a track to guide the sash in its opening and closing movements.

6. In a railway car, the combination with a vestibule having side window openings and a fixed sash in each opening and a center window opening, of a sash movably mounted in the latter opening, an actuating support connected to such sash and adapted to move it to and from such opening, a guideway or track mounted across one of the side window openings and outside of the fixed sash, and a connection between such track or guide and the movable sash to sustain and guide that part of the sash when manipulated by the actuating support.

7. A railway car, having a vestibule provided with a central opening, an opening at either side thereof, fixed window sashes in the side openings, removable sash for the central opening, an actuating support to support said latter sash in movements to and from said central opening, means to secure said support to the vestibule and to the window sash, and a track to guide said movable sash in its opening and closing movements.

8. A railway car having a vestibule provided with a central opening, an opening at either side thereof, fixed window sashes in the side openings, a removable sash for the central opening, an actuating support to support said latter sash in movements to and from its opening, means to secure said support to the vestibule and to the window sash, a guide member securely fastened to the sill in front of one of the fixed window sashes, and means secured to the movable sash to co-operate with the guide member to guide said sash in its opening and closing movements.

9. In a railway car, the combination with a vestibule having a plurality of openings adapted to receive window sashes, of an actuating support for one of said sashes, brackets in which said support is pivotally mounted, so that said sash may be moved into open and closed positions, a guide way mounted on the vestibule in front of one of the openings, other brackets mounted on the sash having the support, and carrying a member adapted to travel on the guideway in the opening and closing movements of said sash, and a spring connected to one of the first mentioned brackets and to said support to cause the sash to fit tightly in place when the window is closed and to prevent the sash from rattling when the window is open.

10. In a railway car, the combination with a vestibule having a plurality of openings adapted to receive window sashes, of an actuating support for one of said sashes, brackets in which said support is pivotally mounted, so that said sash may be moved into open and closed positions, a guideway mounted on the vestibule in front of one of the openings, other brackets mounted on the sash having the support, and carrying a member adapted to travel on the guideway in the opening and closing movements of said sash, a spring connected to one of the first mentioned brackets and to said support to cause the sash to fit tightly in place when the window is closed and to prevent the sash from rattling when the window is open, and a bumper adapted to cushion the sash carried on the support when moved into open position.

In testimony whereof, I affix my signature.

THOMAS ELLIOTT.
